[57] ABSTRACT

A current limiting fuse including an improved fuse element. The fuse element or link includes portions or regions of reduced cross-section which melt during overload to form a series of voltage arclets. The fusible material of the fuse element between notched regions of reduced cross-section is uniquely shaped to take advantage of electrical potential distribution within it, and the natural tendency of electrical current to flow from notch to notch in specified paths of least resistance. The fuse link has a predetermined geometric shape to accommodate the flow of current in an efficient manner and to eliminate those portions of the fuse link which conduct little or no electrical current during normal operation.

CURRENT LIMITING FUSE INCLUDING IMPROVED FUSE ELEMENT

BACKGROUND OF THE INVENTION

This invention relates to electrical current limiting fuses and it has particular relationship to the shape of each fuse element in a current limiting fuse structure.

current limiting fuses may be of the cartridge type and may include elongated sections or elements of fusible material or links between electrically conducting end ferrules. The fuse material may be enclosed in an insulating casing which is disposed between and attached to the conducting end ferrules and which may surround a pulverulent, arc quenching material such as quartz sand which, in turn, may completely or partially enclose or surround the previously mentioned fuse element or elements. The fuse elements may be notched or otherwise reduced in cross-section at specific points along their length. This is especially true where the fuse is of the higher voltage type wherein a plurality of serially spaced arclets is desired to be established upon blowing of the fuse. Often the fuse material is ribbon shaped, or it has a very small thickness compared with its width and length. Generally the fuse element includes one or more regions of limited cross-section to establish and maintain one or more corresponding electrical arcs for a predetermined period of time to limit the current which may attempt to continue to flow through the fuse at the time of fusing. In one type of fuse element, triangularly shaped notches are provided which may be symmetrical about the longitudinal center line of the fuse element. In another fuse, elements having square notches may be used. In other instances, circular or curved sections may be removed from the inner portion of the fuse element. A well known geometric configuration is the triangularly notched configuration mentioned above. Along the length of the fusible material, sections of fuse material having the characteristic shape of an isosceles triangle are removed in a near apex-to-apex relationship, symmetrical about the longitudinal center line. This may be done at fixed intervals along the length of the fusible material. The resultant fuse element may appear to be of a ribbon shape having periodically placed or axially spaced conducting sections which are joined by small notches. The apex of the isosceles triangles may be truncated so that the notched section may be slightly elongated. The reduction in cross-section of the fusible material increases the resistance of the ribbon-like fuse material. As the current flow is traced along the length of the fuse it can be seen that current density is relatively higher in the regions of the previously mentioned notches and lower in the regions of larger cross-section. Since current flows from a notched area into an area of larger cross-section otherwise known as the heat dissipating regions of the fusible material, it would be advantageous and useful to change the shape of the fuse element in the area of larger cross-section to conform to the actual path of the current into and through that region.

SUMMARY OF THE INVENTION

In accordance with the invention a current limiting

fuse comprises a fuse element or link having a plurality of areas of reduced cross-section and a unique geometric shape between successive areas of reduced cross section to more efficiently conduct electrical current flowing through the fuse element. The resultant fuse element has a gently curving or arcuate shape between spaced portions of reduced cross-section which starts at a narrow restricted neck or notch then flows smoothly or gradually outwardly to a bulge or larger section intermediate the adjacent pair of notches and then gradually converges to the next notch of the fuse element. Corners which may be evident on known elements are eliminated because they conduct very little of the total current flowing between the notches compared with the central body of the fuse link or element. The resistance and heat dissipating qualities of the fuse element are not affected or reduced appreciably.

BRIEF DESCRIPTION OF THE DRAWINGS

- 20 For a better understanding of the invention reference may be had to the preferred embodiments exemplary of the invention shown in the accompanying drawings in which:
- 25 FIG. 1 shows a prior art current limiting fuse element with a known shape;
- FIG. 2 is an enlarged view of a portion of the fuse element shown in FIG. 1;
- 30 FIG. 3 is a further enlarged view of a portion of the fuse element shown in FIG. 2;
- FIG. 4 shows lines of equal electrical potential in a section or portion of the fuse element shown in FIGS. 1, 2 and 3;
- 35 FIG. 5 shows a resistance-analog equivalent circuit of the fuse element shown in FIG. 4;
- FIG. 6 shows a geometric representation of the plotting of a current streamline in a fuse element;
- 40 FIG. 7 shows current streamline distribution in a fuse element;
- FIG. 8 shows a fuse link with constant potential lines and constant current streamlines superimposed; and
- 45 FIG. 9 shows a cartridge type current limiting fuse with contoured fuse element in accordance with the teachings of the invention.

DESCRIPTION OF THE PREFERRED EMBODIMENTS

Referring now to the drawings and FIG. 1 in particular, a prior art fuse element 10 is shown. Fuse element 10 may be made from a ribbon of silver or silver-alloy material 12 having triangular sections removed, forming areas of reduced cross-section such as 14 and 16. The triangular portions removed may be isosceles in shape. At any instant of time, electrical current such as i may flow from left to right or vice versa through fuse element 10. The distribution of the electrical current i in the region of larger cross-section 17 for example, of fuse element 12 is different than the distribution of the current i in the areas of reduced cross-section or notched areas such as 14 and 16. Current i may be direct or alternating electrical current and flow in either left to right or right to left directions.

Referring now to FIG. 2, a longitudinal side elevation of a rectangular fuse element 10 is shown in enlarged form. In this case a longitudinal center line or axis 18 is shown and three lines which are perpendicular to the longitudinal center line 18 are also shown. These are line 20, line 22 and line 24. Notched sections 14 and

16 are shown as well as two larger current carrying fuse element portions or sections 17. Line 20 may be generally equidistant from notch 14 and notch 16 and is generally perpendicular to the longitudinal center line 18. Line 20 is shown on fuse link section 19a. The adjacent fuse link or fuse element section 19b has a line 22 generally perpendicular to center line 18 and generally equidistant from notch 16 and notch 16a. Line 24 substantially bisects the notched region 16 and intersects center line 18 at right angles. Referring to intermediate fuse section 19a, it can be seen that center line 18 and perpendicular or normal line 20 form a coordinate system within fuse link 19a having four generally equal and substantially symmetrical, geometric regions numbered I, II, III and IV. It will be noted that the region indicated by III, that is, the region to the right of perpendicular line 20 and above center line 18 is cross-hatched in the drawings.

Referring now to FIG. 3, an expanded or further enlarged view of link portions 19a and 19b in fuse element 10 is shown in the region of notch 16. Perpendicular center line 24 and longitudinal line 18 are also shown. It should be noted that notched section 16 has a relatively flat outer surface having a length indicated as $2d$ ($d+d$). This is slightly different from the overall view shown in FIG. 2 where notch 16 is shown to be formed from the removal of material shaped like two isosceles triangles disposed generally apex-to-apex and oppositely disposed from each other. As can be seen by referring again to FIG. 2, only the upper left portion of the notched region 16 is shown, and that is the portion which corresponds to region III shown in FIG. 2.

It has been found that electrical current, such as i flowing in fuse section 10 does not distribute itself evenly and homogeneously throughout the entire current carrying material 19a, but rather flows in a manner similar to current in an electrical conductor which is under the influence of skin effect. The exact distribution of current in a fuse link or in a section of fuse link such as 19a, may be calculated by the following method. First, assume that a two dimensional solution of current distribution is satisfactory for deriving current streamlines or electrical potential lines, that is, assume that the current distribution normal to the plane of FIG. 4 is uniform. Second, solve Laplace's equation for potential in a section of current limiting fuse, Laplace's equation being $\nabla^2 V = 0$. Said in another way, the second partial derivative of the potential V with respect to X (the longitudinal direction in the fuse element) plus, the second partial derivative of the potential V with respect to Y (the direction normal to center line 18 in the fuse element) must equal zero. Y is perpendicular to center line 18 and X is parallel to center line 18. The resulting equations are as follows:

$$\nabla^2 V = 0$$

$$(\delta^2 V / \delta y^2) + (\delta^2 V / \delta x^2) = 0$$

The equation for electrical potential is then solved in the traditional manner such as with the use of boundary conditions to aid in the solution.

Referring now to FIG. 4, the fuse link portion 19a as shown in FIG. 2 is shown in enlarged form. Concentrating on region III, it will be noted that region III is

bounded by a perimeter comprised of a slanted or diagonal line 32, a horizontal line 30, the vertical line 34, the horizontal center line 18 and the vertical line 24. These peripheral lines may be useful to establish the boundary conditions for solution of equations (1) and (2). The first condition which must be met is that no current must flow out of the periphery of the fuse link, that is, no current may flow through peripheral lines 30 or 32 in region III. The second boundary condition is that distribution of electrical potential must be a mirror image of itself about the center line 18. This means that there will be no flow of current across center line 18. This is one reason why a relatively small but well defined region may be useful to find potential distribution for the entire fuse section or link 19a. The third boundary condition is that a constant potential line equidistant between two notches such as 16 and 14 and perpendicular to center line 18 will be an isopotential line. Line 34 meets this requirement. The fourth condition is that a line perpendicular to center line 18 in the center of the notched region or in region 16 and equidistant from the two ends of the notches or at a distance d from point 23 as shown in FIG. 3 will also be an isopotential line, at some potential other than that of line 34. Examination will show that perpendicular line 24 meets this requirement. Using these four boundary conditions the Laplace equation may be solved producing a solution for electrical potential. The solution is: a constant C_o times X plus the sum from $N=1$ to infinity of the quantity C_n times the hyperbolic sine of the subquantity $N \pi X / L_2$ times the cosine of the subquantity $N \pi Y / L_2$. N in this case is an integer, X is the distance from the intersection of lines 18 and 34 or the lower left corner of region III in a direction from left to right, Y is the vertical direction from the intersections of lines 18 and 34 upward, and C_n and C_o are constants which are determined by application of the previously named boundary conditions. L_1 is the longitudinal distance between perpendicular lines 34 and 24 and L_2 is the vertical distance between longitudinal center line 18 and periphery line 30. The equation may be written thusly:

$$V = C_o X + \sum_{N=1}^{\infty} C_n \sinh \frac{(N\pi X)}{L_2} \cos \frac{(N\pi Y)}{L_2} \quad (3)$$

The above equation is a closed-form solution for potential distribution in a model of a notched current limiting fuse with the added criterion being that an orthogonal coordinate system must be used. A plot of equipotential, ($V = \text{constant}$), distribution lines within region III is shown in FIG. 4. In this case, five equielectrical-potential lines are shown at 34, 36, 38, 40 and 42. It will be noted that equipotential lines 34 and 36 meet the boundary conditions of being perpendicular to center line 18 and straight. Since the distribution of potential region III is similar to regions I, II and IV, the equipotential lines may be drawn throughout the entire fuse link 19a as shown by equipotential lines 44, 46, 48 and 50 in addition to those previously mentioned. The Cauchy-Riemann criterion is now used to arrive at an equation for current streamlines or the stream function Ψ . This may be verified by referring to page 148 of the reference book "Principles and Applications of Electromagnetic Fields" by R. Plonsey and R. E. Collin published by the McGraw-Hill Book Company, Inc.

The Cauchy-Riemann criterion states that a relationship exists between potential V and a stream function Ψ such that:

$$\delta V/\delta X = \delta \Psi/\delta Y$$

4.

$$\delta V/\delta Y = -\delta \Psi/\delta X$$

5.

That is, the partial derivative of potential with respect to X equals the partial derivative of the stream function with respect to Y , and the partial derivative of potential with respect to Y equals the negative of the partial derivative of the stream function with respect to X . Now the current density in the X direction, j_x , at any point (X, Y) in the fuse element is related to potential by:

$$j_x = -(1/\rho) \delta V/\delta X$$

or, in terms of the stream function from Equation (4):

$$j_x = -(1/\rho) \delta \Psi/\delta Y$$

7.

At any point X the total current flowing in the X direction, that is in the direction of the longitudinal center line 18, between the longitudinal center line 18 and any point Y , is given by

$$i = T \int_0^Y j_x dy \quad (8)$$

where T is the thickness of the element ribbon, normal to the coordinates X and Y . From Equations (6) and (8) it follows that

$$\begin{aligned} i &= -T \int_0^Y \left(\frac{\partial \Psi}{\partial Y} \right)_{x=0} dy \\ &= -\frac{T}{\rho} \int_0^Y \left(\frac{\partial V}{\partial X} \right)_{x=0} dy = -\frac{T}{\rho} \psi(X, Y) \end{aligned} \quad (9)$$

From Equation (9) it can be seen that a definite relationship exists between the stream function Ψ at point X, Y in the fuse element and the total current flowing in the X direction between longitudinal center line 18 and the point X, Y . The total current flowing in the X direction between the longitudinal center line 18 and periphery lines 30 and 32 is:

$$I = -\frac{T}{\rho} \int_0^{L_2} \left(\frac{\partial \Psi}{\partial Y} \right)_{x=0} dy = -\frac{T}{\rho} \int_0^{L_2} \left(\frac{\partial V}{\partial X} \right)_{x=0} dy = -\frac{T}{\rho} \psi(X, L_2) \quad (10)$$

Now a nondimensional stream function can be defined as

$$\bar{\Psi}(X, Y) = \Psi(X, Y)/\Psi(X, L_2)$$

11.

From Equations (9), (10), and (11) it can be seen that the nondimensional stream function $\bar{\Psi}(X, Y)$ is the fraction of the total current flowing in the direction of the longitudinal center line 18 which flows between the longitudinal center line 18 and point X, Y . Likewise, Equations (9), (10), and (11) show that the nondimensional stream function $\bar{\Psi}(X, Y)$, or current fraction,

can be determined mathematically from Equation (3), which is a mathematical expression for potential V at point X, Y .

Referring now to FIG. 6, a portion of fuse element 10 or link portion 19a, region III is shown. Center line 18 forms the bottom-most portion of the fuse element portion shown. Here two constant potential lines $V = C_1$ and $V = C_2$ are shown. At some point P, having coordinates X, Y , on the constant potential line $V = C_1$, the nondimensional stream function $\bar{\Psi}$ has a value of K where $0 \leq K \leq 1$. Likewise on the constant potential line $V = C_2$ there is a point Q which has the same value of nondimensional stream function K . By considering many such lines of constant potential, a point on each such line can be found where the nondimensional stream function $\bar{\Psi}$ equals K . By drawing a line through these points of constant nondimensional stream function $\bar{\Psi} = K$ a current streamline is defined as shown in FIG. 6. At each point on this line the nondimensional stream function $\bar{\Psi}$ has the value K . By definition of the nondimensional stream function, at every point along the streamline $\bar{\Psi} = K$ the fraction of the total current flowing in the direction of the longitudinal center line 18 which flows between the longitudinal center line 18 and the streamline $\bar{\Psi} = K$ is K . Thus no current flows across the streamline $\bar{\Psi} = K$.

Referring now to FIG. 8, a plot of nondimensional stream function equicurrent streamline $\bar{\Psi}$ is shown. The longitudinal center line 18 has a value of $\bar{\Psi} = 0$ and the peripheral boundaries 30 and 32 have a nondimensional stream function value of $\bar{\Psi} = 1.0$. Referring back to Equation (3), since the hyperbolic sine function is odd and the cosine function in the mathematical definition of potential V is even, then V at a point $(X, -Y)$ equals V at point (X, Y) and V at a point $(-X, Y)$ equals $-V$ at point (X, Y) . That is, the distribution of potential V in region IV is a mirror image about the longitudinal center line 18 of the distribution of potential V in region III. Likewise the distribution of potential V in region I is a mirror image about the perpendicular center line 20 of the distribution of potential V in region III with the sign changed and potential V in region II is a mirror image about line 34 of the potential V in IV with the sign changed. It follows from the Cauchy-Riemann criterion that the inverse of these mirror image laws apply to the nondimensional stream function $\bar{\Psi}$. Thus FIG. 8 shows lines of constant potential and streamlines for the entire link 19a.

It will be noted that a psi normal ($\bar{\Psi}$) equals 0.5 plot is depicted in FIG. 7. This means that 50 percent of the total current flows between the psi normal ($\bar{\Psi}$) equal 0.5 curve and the center line 18. This is represented by the hatched or shaded area 27.

Referring now to FIG. 8, a composite plot of normalized equicurrent streamlines in a complete fuse link 19a is shown. The potential lines are represented by lines 34, 38, 40, 42, 46, 48 and 50, and the streamlines are represented by $\bar{\Psi}$ equal 0, $\bar{\Psi}$ equal 0.25, $\bar{\Psi}$ equal 0.5, $\bar{\Psi}$ equal 0.75 and $\bar{\Psi}$ equal 1. An important aspect of the invention may be recognized by realizing that the area enclosed between the two shown psi normal equals 0.75 lines represents a significant portion of the conducting link 19a and by also noticing that 75 percent of the entire electrical current flowing between notch 16 and notch 14 must flow within the psi normal equals 0.75 lines adjacent to the top and bottom of link portion 19a. Consequently, all of the electrical material

above the psi normal equals 0.75 line in the top part of section or link 19a and below the psi normal equals 0.75 line in the bottom part of fuse link portion or section 19a may be removed and 75 percent of the current will still flow in the remaining conducting material of the fuse link 19a with the same potential applied across the fuse. Of course, this construction increases the electrical resistance in element section 19a from R to $R/0.75 = 1.33R$.° but does not increase it in the same proportion to the decrease in current carrying capacity. For example, although, not shown, a Ψ equals 0.95 curve may be superimposed on conductor link portion 19a and that part of the conductor link outside or not included within the region described by the psi normal equals 0.95 line may be removed and 95 percent of the electrical current will continue to flow, in fuse link 19a with the same electrical potential applied across the fuse. However, the removed portion constitutes a rather significant physical amount of the fuse link portion 19a. In summary, this means that most of the current flowing in a tapered or notched fuse portion such as 19a as shown in FIG. 8 flows in the center of the fuse element when viewed from the side so that the corners or edges may be eliminated providing a slight increase in resistance to the fuse element or link portion 19a but providing a larger significant decrease in the amount of material used to form the fuse link or element without a significant reduction in the current carrying or conducting capacity, simply because a significant amount of current does not flow in the peripheral, outer portion of the fuse link portion 19a.

Referring now to FIG. 9, a cartridge type current limiting fuse structure 58 embodying a fuse link or fuse element 60 is shown having regions of reduced cross-section such as 14 and 16, the periphery 76 of which is determined by the criteria previously described. Line 76 may have the shape of an electrical current streamline which may be calculated through the use of the Cauchy-Riemann criterion and the Laplace equations for potential in the fuse link 60. It will be noted that fuse structure 58 as shown in FIG. 9 has end ferrules 64 and 66, a tubular insulating member or housing 68 disposed between the end ferrules or electrical conducting members 64 and 66, and enclosing arc quenching pulverulent material 70 which may be quartz sand. The fuse link or element 60 which may be connected and disposed between one electrically conducting interface member 72 which is adjacent to both one end of the fuse link 60 and the electrically conducting ferrule 64 and a similar interface means near ferrule 66 not shown. Current may then flow through the electrical fuse 58. However, a significant amount of fusible material in fuse link or element 60 has been removed prior to construction.

It is to be understood that the previously described use of current streamline construction to determine the exact shape of current limiting fuses having areas of reduced cross-section may be determined by other methods than the computer oriented mathematical approach previously described. The use of trial and error

is proper as is the use of plotting potential distribution on resistive paper. It is also to be understood that as long as an orthogonal coordinate system may be developed for a fuse link, that any shape of reduced cross-section including square shaped or rectangularly shaped notched sections or even circularly notched sections may be used. It is also to be understood that this invention need not be applied only to cartridge type current limiting fuses nor need it be applied only to current limiting fuses having single fuse elements.

The apparatus embodying the teachings of this invention has several advantages for example, an advantage lies in the more efficient use of a fuse element in a current limiting fuse to carrying the maximum amount of current in any given cross-section of material without using unnecessary material which carries very little current. An overall reduction in fuse link size and a corresponding reduction in fuse structure are also advantages.

20 We claim as our invention:

1. An electrical fuse comprising spaced terminals and a fuse element of fusible material, said fuse element being electrically connected to and interposed between said spaced terminals, the dimensions of a planar portion of said fuse element being definable in a two-dimensional orthogonal coordinate system, at least a portion of the peripheral shape of said planar portion of the said fuse element being defined by the non-dimensional stream function, wherein said non-dimensional stream function is less than 1 and greater than zero.

2. An electrical current limiting fuse comprising a pair of spaced terminals, a fuse element formed from fusible material, said fuse element being electrically connected and interposed between said terminals, said fuse element having at least one region of reduced cross-section, the dimensions of a planar portion of said fuse element being definable in a two-dimensional orthogonal coordinate system, at least a part of the outer periphery of said planar portion of said fusible material, not including a substantial portion of any said region of reduced cross-section, being defined by the non-dimensional stream function, wherein said non-dimensional stream function is less than 1 and greater than zero.

3. The combination as claimed in claim 2 comprising pulverulent arc quenching material disposed proximate to at least a portion of said fusible material, a tubular outer shell of insulating material, said outer shell being disposed between said terminals and attached thereto to form an enclosure around said fuse element and said arc quenching material

4. The combination as claimed in claim 3 wherein said fusible material comprises a silver based alloy and said arc quenching material comprises quartz sand.

5. The combination as claimed in claim 4 wherein said non-dimensional stream function has a value in a range greater than zero but less than or equal to 0.95.
